UNITED STATES PATENT OFFICE.

WILLIAM RATLIFF, OF MONTREAL, QUEBEC, CANADA.

HELICOPTER.

Application filed June 18, 1923. Serial No. 646,179.

To all whom it may concern:

Be it known that I, WILLIAM RATLIFF, a citizen of the United States of America, residing at Montreal, Province of Quebec, Canada, have invented certain new and useful Improvements in Helicopters; and I do hereby declare that the following is a full, clear, and exact description of the invention, such as will enable others skilled in the art 10 to which it appertains to make and use the same.

The present invention pertains to novel improvements in flying machine structures, particularly of the helicopter type.

15 The principal object of the invention is the provision of a device of this character having a substantially vertical propeller shaft on which is carried suitable elevating means. Such means includes a plurality of vanes 20 which are normally inclined at an angle to the horizontal. The invention resides, in one respect, in a simple and efficient means for regulating the inclination of the blades independently and as desired. To this end, the 25 outer extremities of the vanes are each connected to the intermediate portion of the shaft by means of a pair of guy wires. One wire of each pair has a turn buckle inserted therein which may be operated to adjust the 30 elevation of the particular portion of the vane to which it is connected. Consequently the inclination of that vane is adjusted.

Another feature of the invention is the 35 mounting of a plurality of cones on the propeller shaft, these cones being upright and having their axes in line with the shaft. The object of these cones is to decrease air resistance as will be obvious to those skilled in the art.

40 A further object of the invention is to provide a simple and efficient bracing means for maintaining the propeller shaft in upright position with relation to the body of the machine. This structure includes a bridge 45 and various braces pointed out in detail below.

The invention is fully disclosed in the following description and in the accompanying drawings in which:

50 Figure 1 is a side elevation of the device;
Figure 2 is a longitudinal section of the body;
Figure 3 is a vertical transverse section thereof;
55 Figure 4 is a plan view of the device;

Figure 5 is a fragmentary vertical elevation through the propelling mechanism; and,

Figure 6 is a section on the line 6—6 of 60 Figure 4.

Reference will now be had to these views by means of like characters which are employed to designate corresponding parts throughout.

The device comprises a body 1 mounted 65 on wheels 2, one end of the body being formed with a hood 3. Within the hood is mounted a motive mechanism (not shown) from which extends a power shaft 4. A bearing block 5 is placed in the bottom of 70 the body and a similar block 6 is placed across the top thereof for supporting a counter shaft 7. The lower end of this shaft carries a ring gear 8 meshing with a bevel gear 9 secured to the end of the power 75 shaft 4.

A bridge 10 extends transversely across the body and is secured to the sides thereof as illustrated in Figure 3. Directly beneath the top 11 of the bridge, a bearing block 12 80 is secured to the sides of the body 1 and supports the lower end of the propeller shaft 13 which passes through the top 11. The lower end of this shaft carries a gear 14 which meshes with a pinion 15 on the counter shaft 7. By means of the gearing thus far described, the propeller shaft is driven 85 from the motive mechanism.

The upper portion of the propeller shaft carries a plurality of upright cones 16, the 90 axes of which are in line with the shaft. These cones are each supported upon a base 17 bolted to a clamp 18 secured to the shaft, as clearly illustrated in Figures 5 and 6. A plurality of wings 19 extend radially outward from each base, the inner ends thereof being passed through the bottom of the corresponding cone. The wings are tilted by means of wedges 20 being inserted between the inner ends thereof and the top of the 95 base. These parts are assembled and locked together by means of bolt and nut devices 21 passed therethrough.

The propeller shaft has fixed thereto a collar 22 resting on the top 11 to prevent 105 downward slipping of the shaft, and this collar carries a disk 23. For properly supporting the outer ends of the wings, guy wires 24 extend from the periphery to the disk angularly through the lower vanes 110

and thence vertically, in the nature of spacers 25, to the upper vanes. Nuts 26 are threaded on the spacer portions in engagement with the upper surfaces of the vanes 5 for preventing slipping of these members. Each set of vanes is supported by a pair of guy wires, one of which is fitted with a turn buckle 27. This device may be adjusted to vary the elevation of one of the 10 outer corners of a vane whereby the inclination of the corresponding set of vanes is altered. It will be apparent that by means of the turn buckles, the inclination of the vanes may separately be adjusted as 15 desired.

The propelling structure is maintained upright with relation to the body by means of braces 28 engaging opposite edges of the 20 sides of the bridge 10 and secured to the sides of the body, as shown in Figure 1. Provision against lateral shifting of the shaft 13 with relation to the body is obtained by mounting braces 29 and 30 upon the blocks 6 and 14 respectively, these 25 braces engaging the inner sides of the bridge, as shown in Figure 3.

While a specific embodiment of the invention has been illustrated and described, it 30 is to be understood that various alterations in the details of construction may be made without departing from the spirit of the invention as indicated by the appended 35 claims.

Having thus fully described the invention, what I claim as new and desire to protect by Letters Patent is:—

1. A helicopter comprising a body and a propeller shaft extending vertically therefrom, means for rotating said shaft, a plurality of cones carried in upright position by said shaft and having their axes in line therewith, vanes having their inner ends secured in the bottoms of said cones, bases 40 associated with said cones, and wedges inserted between the tops of said bases and 45

the inner ends of the vanes for tilting said vanes.

2. A helicopter comprising a body and a propeller shaft extending vertically therefrom, means for rotating said shaft, a plurality of cones carried in upright position by said shaft and having their axes in line therewith, vanes having their inner ends secured in the bottoms of said cones, a disk 55 carried by the shaft and disposed beneath the cones, a pair of guy wires extending from said disk to each of said vanes, and a turn buckle inserted in one of the guy wires of each pair.

3. A helicopter comprising a body and a propeller shaft extending vertically therefrom, means for rotating said shaft, a plurality of cones carried in upright position by said shaft and having their axes in line therewith, vanes having their inner ends 60 secured in the bottoms of said cones, bases associated with said cones, wedges inserted between the tops of said bases and the inner ends of the vanes for tilting said vanes, a disk carried by the shaft and disposed beneath the cones, a pair of guy wires extending from said disk to each of said 65 vanes, and a turn buckle inserted in one of the guy wires of each pair.

4. A helicopter comprising a body, a bridge extending transversely thereof, a bearing block supported in the body and beneath the top of said bridge, a propeller shaft supported in said top and block, a counter shaft, means for driving said counter 75 shaft, a drive connection between the counter shaft and propeller shaft, braces mounted on the sides of the body and engaging the top of the bridge, and additional braces mounted on the bearing blocks 80 and engaging the inner sides of the bridge.

In witness whereof I have hereunto set my hand.

WILLIAM RATLIFF.
